UNITED STATES PATENT OFFICE

2,561,413

SORTING MACHINE

James D. Auman, Lancaster, Pa., assignor to Armstrong Cork Company, Lancaster, Pa., a corporation of Pennsylvania

Application February 1, 1947, Serial No. 725,787

9 Claims. (Cl. 209—72)

1

The present invention relates to sorting machines and, more particularly, to a machine for sorting generally cylindrical objects, such as wood tops for corks. The invention is not limited to the sorting of such articles, however, but will be found useful in the sorting of other generally cylindrical articles which are capable of being rolled on edge.

It is an object of my invention to provide an apparatus which will receive generally cylindrical articles promiscuously fed thereto with some of the articles facing in one direction and others of the articles facing in the opposite direction and will sort and position such articles so that all will be disposed in one direction with a predetermined face disposed upwardly.

Another object of my invention is to provide a sorting apparatus of the type mentioned above which will be effective for discharging defective articles prior to the final positioning of the acceptable articles with their flat faces upwardly.

Further objects of my invention will be clear from the description which follows.

In the manufacture of cork stoppers having wood tops, the tops are frequently embossed and are decorated with colored inks, lacquers, enamels, or the like prior to assembly of the tops with the cork stoppers. The machines which are used for coating or decorating the tops receive the tops with their top surfaces disposed upwardly so that the decorating ink or other coating material may be applied thereto. The coating machines generally are of an automatic nature and operate upon a plurality of the tops simultaneously. After the decorating operation, the tops are frequently fed to a drying oven, and, after completion, to an assembly machine where the tops must be disposed with their bottom sides up so that adhesive may be applied and the corks positioned thereon for joining of the corks and tops. It is necessary in such operations, therefore, to sort the tops and align them for these operations.

In the manufacture of the tops, it frequently happens that the wood is imperfect, and this results in defective tops. One of the most common defects is incomplete or broken-edge formation, and this defect may not be readily detected by the inspectors, unless the tops are individually rotated within their vision.

According to my invention, the tops are fed to an inclined trackway with some of the tops facing in one direction and others facing in the opposite direction. The trackway is covered with a frictional material which prevents the articles

from slipping and insures that they rotate in their travel down the trackway. The articles have a greater diameter adjacent one face than they do adjacent the other, and, as a consequence, when they are rolled, they tend to describe an arcuate path. Defective articles, particularly where the skirt portions of the articles are incomplete or broken away, do not follow a true arcuate path, and their direction of motion is not predictable, for when the articles rotate to a position where a defect is in engagement with the trackway, the path of movement may be and frequently is at a sharp angle with respect to the normal path of movement. The trackway is divided into two segments, and guides are provided for each segment to limit the arcuate path of travel of the acceptable articles. The articles come into rolling engagement with the guides, with one of their flat surfaces lying in engagement therewith. The divergent portions of the trackway are separated by an open area, and articles, such as the defective ones mentioned above, which do not follow the guides but move irregularly with respect to the normal path of movement, drop through this opening and are discharged from the machine.

In order that my invention may be more readily understood, I shall describe the same in connection with the attached drawings, in which:

Figure 1 is a diagrammatic assembly view showing the mechanism of my invention attached to a hoppering and feeding device and disposed to feed articles to a decorating machine;

Figure 2 is a top plan view illustrating the trackway of my invention;

Figure 3 is a sectional view taken on the line III—III of Figure 2;

Figure 4 is a sectional view taken on the line IV—IV of Figure 2;

Figure 5 is a top plan view of a pair of guiding chutes for attachment to the trackway of Figure 2, the chutes being shown to a slightly larger scale than in the trackway in Figure 2;

Figure 6 is a side elevation of one of the guide chutes of Figure 5;

Figure 7 is a diagrammatic view illustrating the disposition of articles on the trackway of Figure 2;

Figure 8 is a schematic view showing the movement of the articles to be sorted from a conveyor belt onto the trackway of Figure 2;

Figure 9 is a perspective view of an article which the machine of the present invention is adapted to sort;

Figure 10 is a sectional view taken on the line X—X of Figure 5;

Figure 11 is a sectional view taken on the line XI—XI of Figure 5; and

Figure 12 is a perspective view illustrating a defective article similar to the article of Figure 9 which the sorting device of this invention will reject.

Referring to Figure 1, there is shown a feeder 2 which may be of the type disclosed and claimed in the copending application of George Paul Potter, Serial No. 724,763, filed January 28, 1947. In place of the feeding device shown, any other feeder which is effective for disposing the articles on edge and conveying them to my sorting mechanism may be employed. The sorter of the present invention is indicated generally at 3 in Figure 1 and is effective for delivering articles 4 onto a conveyor belt 5 which continuously carries the articles into and through a decorating mechanism 20 diagrammatically illustrated by the box 6. The articles, after decoration in the unit 6, move down a chute 7 onto a belt 8 which conveys the articles into a drying oven. A discharge chute 9 is provided for conveying defective or rejected articles from the trackway 3 into a tote box 10 or other receptacle.

Referring now to Figure 2, the trackway 3 may be formed of sheet metal, as shown, or, if desired, may be formed of wood or other material. The trackway 3 is secured to the hopper 2 at one end and, in the embodiment illustrated, is inclined at an angle of about 5° to the horizontal. The degree of inclination will depend to some extent, of course, upon the nature of the articles being sorted, their size and geometric configuration. The inclination should be maintained as small as possible but must be effective to permit the articles to roll freely and with dispatch therealong.

The trackway 3 has a bottom 11 which, adjacent the entrance end thereof, is of a width slightly greater than the axial length of the articles being operated upon. The bottom 11 increases in width from its entrance end to a point 12 where the trackway is divided into two segments, 13 and 14. Thus, the trackway has a relatively narrow delivery end and a gradually widening discharge end, and there is a wide, flat, unobstructed orienting surface on the trackway between the ends which, as shown in the drawings, is more than twice as wide as the width in an axial direction of the articles to be sorted. An opening 15 is provided between the segments 13 and 14, and this opening is of a width adjacent the exit end of the trackway substantially greater than the axial length of the articles being operated upon and tapers to the point 12. This opening must be of a size sufficient to pass rejected articles therethrough.

The bottom 11 of the trackway 3 is covered with a covering 16 of frictional material, such as a sheet of cork composition. This insures that the articles moving thereover will not slide on the surface but will be rotated. This is particularly desirable where the peripheral surface of the articles being treated is knurled or corrugated, as frequently occurs in wood tops. The covering, preferably, extends throughout the whole length of the trackway, including the segments 13 and 14 thereof.

The covering 16 is arched along the line 17, shown in Figures 2 and 7, by means of a wire 18 or similar piece of material secured to the bottom 11 of the trackway. Corresponding members 19

and 20 are provided adjacent the inside edges of the segments 13 and 14 to curve the surfacing material upwardly, as shown in Figures 2 and 4.

Referring now to Figure 9, there is shown an embossed wood top 21 which is provided on its bottom surface with a recess 22 which receives a cork stopper, the same being adhesively joined to the wood top. The skirt of the top is knurled, as indicated at 23, and there is a bead 24 on the periphery adjacent the bottom. As will be noted from examination of this figure and the tops shown in Figures 7, 10, and 11, the diameter of the top at the bead 24 is greater than the diameter at the top surface 25. Thus, if the top 21 is rolled on edge, it will tend to describe an arc in its travel, the top moving in the direction of the smaller diameter 25. The radius of the arc described will depend upon the difference in diameter between the bead 24 and the top surface 25 and the axial distance between the surface-engaging lines on the top, but, in most instances, the radius of the arc will be fairly large. In a stopper top, such as shown in Figure 9, the radius will be in the neighborhood of 11".

The articles fed by the feeder 2 are disposed in single file at the entrance end of the trackway 3. Some of the articles will face in one direction and others will face in the opposite direction. A rolling motion will be imparted to the tops as they move down the inclined trackway, and since the articles have a greater diameter adjacent one face than adjacent the other, as previously mentioned, they will describe an arc, and those which have the smaller diameter facing to the right will move in that general direction until they come into engagement with a guide 26, as shown in Figure 4. Those having the smaller diameter facing to the left will move in an arc until they engage the guide 27. The articles will continue to roll down the trackway 3, and since their natural tendency is to move in directions toward the guides 26 and 27, the articles will lie closely adjacent thereto throughout the length of the trackway.

In order to insure that the articles are directed to their proper location in their initial movement from the entrance end of the trackway to a position where their outer edge surfaces are in engagement with the guides 26 or 27, the wires 18, 19, and 20 are provided so as to arch the lower surface of the trackway upwardly; thus, any articles which move toward such arched portions will be immediately deflected and caused to move toward their guide members 26 or 27.

The distance from the entrance end of the chute 3 to the point 12 where the segments 13 and 14 diverge should be of sufficient length to permit the tops to orient themselves adjacent the guides 26 and 27. The same is true of the arched portion 11 which divides the trackway bottom 11 into the segments 13 and 14. This length will depend upon the diameter of the articles being sorted and the arc which they describe, which, as mentioned above, depends upon the difference between the diameters of the inner and outer surfaces and their axial length. With a top $1\frac{5}{8}$ " in diameter at the lower surface and $1\frac{1}{8}$ " in diameter at the top surface and an axial length of $\frac{3}{8}$ ", the distance from the entrance end of the trackway 3 at the line 28 to the point 29 may be about 7", and from the line 28 to the point 12 about 20". The length of the trackway from its feed end 28 to the exit end of the segments 13 and 14 may be about 27", with the opening 15 about $2\frac{1}{4}$ " at the base and 7" long.

Figure 12 illustrates a defective top in which the skirt head 24 is partially broken away, as indicated at 30. As mentioned above, this may occur by reason of defects in the wood blank from which the top is formed. It is desirable to eject such defective tops from the machine, and the device of the present invention is effective for removing such defective tops.

A defective top, such as that shown in Figure 12, when moving down the trackway 11, will start to describe an arcuate path until the defective portion 30 comes into engagement with the trackway; whereupon, the article will take an erratic movement to the right or left and may go completely across a trackway until the broken-out portion 30 again engages the surface; whereupon, a further movement will occur. When the top reaches a position, such as shown at 31 or 32 in Figure 7, the top will drop through the opening 15, and, as shown in Figure 1, will fall into the chute 9 and be delivered into the tote box 10.

The satisfactory articles moving down the segments 13 and 14 must be turned through 90° to bring the desired flat faces upwardly. In the embodiment shown in Figure 1, where the top surfaces of the wood tops are to be decorated, the articles must be moved to a position where all of them have their top surfaces upwardly, that is, the reverse of the position shown in Figure 9. This is effected by means of the chutes shown in Figures 5, 6, 10, and 11. These chutes 33 and 34 are of opposite hand. The chute 33 is provided with a left-hand twist of 90°, and the chute 34 is provided with a right-hand twist of 90°. The chutes are generally of rectangular cross section, as shown in Figures 10 and 11, and are preferably formed of a sheet metal tube which is filled with a plastic material and twisted, the plastic material being then melted out. The articles rolling down the segment 13 into the chute 33 enter in the position shown in Figure 10. They are rotated through 90° in passage through the chute 33 and are discharged in the position shown in Figure 11 onto the conveyor belt 5. The articles moving down the segment 14 of the trackway 3 enter into the chute 34 and are rotated through 90° which brings their upper surfaces to the top, as indicated in Figure 11, so that all of the tops are fed to the machine with their top sides up.

Where the device is to be used for presenting wood tops to an assembly machine or other operation where the bottom sides should be up, the chutes 33 and 34 will be reversed so that the chute 33 will have a right-hand twist and the chute 34 a left-hand twist. This will be effective for moving the articles through 90°, in each instance to bring the tops into a position where the bottom faces are disposed upwardly.

While I have illustrated and described a preferred embodiment of my invention, it will be understood that the same may be otherwise embodied and practiced within the scope of the following claims:

I claim:

1. In a device for sorting articles such as stopper tops or like substantially cylindrical articles having a diameter adjacent one face greater than adjacent the other, said articles being fed to the device on edge with some of the articles facing in one direction and some in the opposite direction, to position the articles all in one direction with a selected flat face disposed upwardly, the combination of an inclined trackway down which the articles roll on edge, said trackway being

divided into two divergent portions with an opening therebetween for the passage of defective articles, and guide members defining the outer edges of the trackway, said trackway being substantially unobstructed adjacent said opening to permit defective articles to pass therethrough.

2. In a device for sorting articles such as stopper tops or like substantially cylindrical articles having a greater diameter adjacent one face than adjacent the other and which describe an arcuate path when rolled on edge to separate the same from defective blanks of a similar nature but not of regular peripheral contour and which describe an erratic path when rolled on edge, said articles and blanks being fed to the device on edge with some of the articles and blanks facing in one direction and some in the opposite direction, to position the articles all in one direction with a selected flat face disposed upwardly, and to discharge the defective blanks, the combination of a trackway inclined downwardly from its feed end, said trackway being divided into two divergent portions with an opening therebetween, guide members projecting upwardly from said trackway and limiting outward movement of the articles as they roll along the trackway, and means positioned adjacent the opening to guide articles rolling on said trackway toward said guides and away from said opening but permitting defective blanks to pass thereover and through said opening for discharge from the trackway.

3. In a device for sorting articles such as stopper tops or like substantially cylindrical articles having a greater diameter adjacent one face than adjacent the other and which describe an arcuate path when rolled on edge to separate the same from defective blanks of a similar nature but not of regular peripheral contour and which describe an erratic path when rolled on edge, said articles and blanks being fed to the device on edge with some of the articles and blanks facing in one direction and some in the opposite direction, to position the articles all in one direction with a selected flat face disposed upwardly, and to discharge the defective blanks, the combination of a trackway inclined downwardly from its feed end, said trackway being divided into two divergent portions with an opening therebetween, guide members projecting upwardly from said trackway adjacent the outer edges thereof, a covering of frictional material on said trackway to prevent slippage of said articles and cause the same to roll on edge, means positioned below said covering to curve the same slightly upwardly adjacent said opening to cause said articles while rolling down said trackway to move outwardly from the opening toward said guide members projecting from the trackway, said curved surface being insufficient to deflect said defective blanks from movement over said curved surface and through said opening for discharge from said trackway.

4. In a device for sorting articles such as stopper tops or like substantially cylindrical articles having a greater diameter adjacent one face than adjacent the other, such articles when rolled on edge describing a curved path of movement to separate the articles from defective blanks of a similar nature but not of regular peripheral contour and which describe an erratic path when rolled on edge, said articles and blanks being fed to the device on edge with some of the articles and blanks facing in one direction and some in the opposite direction, the com-

bination of a trackway inclined downwardly from its feed end, said trackway being divided into two divergent portions with an opening therebetween for the passage of defective blanks, and guide means on opposite sides of said trackway for limiting the curved path described by said articles as they roll on edge along said trackway.

5. In a device for transferring articles of a substantially cylindrical nature from a hopper where the articles are disposed on edge with some of the articles facing in one direction and some in the opposite direction to a conveyor where the articles are disposed with a selected flat face disposed upwardly, the combination of a trackway inclined downwardly from said hopper which delivers the articles to the trackway on edge, said trackway having a wide flat surface down which the articles freely and unobstructedly roll on edge in an arcuate path, guides provided at opposite sides of the trackway to limit outward movement of the articles in their travel along said trackway, said trackway being divided into two divergent portions with an opening therebetween for the discharge of defective articles, and a turnover chute adjacent each guide to receive articles moving on edge along said guides, one of said chutes having a right-hand twist and the other having a left-hand twist to turn said articles in their travel therethrough from a substantially vertical to a substantially horizontal position, said trackway delivering said articles selectively to said chutes in accordance with the position of each article as it is delivered to the trackway from said hopper, said chutes being inclined downwardly from said trackway to deliver the articles by gravity to said conveyor with the selected flat face of each article disposed upwardly.

6. In a device for transferring articles of a substantially cylindrical nature from a hopper where the articles are disposed on edge to a conveyor where the articles are disposed with a selected flat face disposed upwardly, the combination of a gravity trackway inclined downwardly from the hopper which delivers the articles to the trackway on edge, said trackway being of substantial width for a portion of its length to permit articles rolling therewith in arcuate paths to move to the right and to the left from the center line thereof to assume a position outwardly from the center, guides for limiting such outward movement of the articles rolling along the trackway, said trackway being divided into two relatively narrow portions adjacent its exit end with an opening of substantial area disposed therebetween for the passage of defective articles which do not follow the guides, and turnover chutes disposed adjacent said guides for receiving articles from the guides selectively on edge in accordance with the position of each article as it enters the trackway and for changing the position of said articles from an edgewise position to a position with a selected flat face disposed upwardly.

7. In a device for sorting substantially cylindrical articles having one face of smaller diameter than the other which will stand on edge, such as stopper tops or the like, and which are fed to the device on edge with some of the articles facing in one direction and some in the opposite direction to position the articles all in one direction with a selected flat face disposed upwardly, the combination of an inclined trackway having a relatively narrow delivery end and a gradually widening discharge end, means for delivering said

articles to said trackway on edge at the delivery end thereof, a wide, flat, unobstructed orienting surface on said trackway between the ends which is more than twice as wide as the width of said articles in an axial direction and down which said articles freely and unobstructedly roll on edge in an arcuate path from said delivery end toward said discharge end, guide members against which the articles are directed in their arcuate movement along said trackway with the small diameter face of each article lying in engagement with one of said guide members, and a pair of inclined chutes associated with said trackway at the discharge end thereof for changing said articles from a position with their axes parallel to the surface of the trackway to a position with their axes perpendicular thereto, one of said chutes having a right-hand twist and the other a left-hand twist, said trackway delivering said articles selectively to said chutes in accordance with the position of each article as it enters the trackway.

8. In a device for sorting substantially cylindrical articles having one face of smaller diameter than the other which will stand on edge, such as stopper tops or the like, and which are fed to the device on edge with some of the articles facing in one direction and some in the opposite direction to position the articles all in one direction with a selected flat face disposed upwardly, the combination of an inclined trackway having a relatively narrow delivery end and a gradually widening discharge end, means for delivering said articles to said trackway on edge at the delivery end thereof, a wide, flat, unobstructed orienting surface on said trackway between the ends which is more than twice as wide as the width of said articles in an axial direction and down which said articles freely and unobstructedly roll on edge in an arcuate path from said delivery end toward said discharge end, a frictional covering material on said trackway, guide members against which the articles are directed in their arcuate movement along said trackway with the small diameter face of each article lying in engagement with one of said guide members, and a pair of inclined chutes associated with said trackway at the discharge end thereof for changing said articles from a position with their axes parallel to the surface of the trackway to a position with their axes perpendicular thereto, one of said chutes having a right-hand twist and the other a left-hand twist, said trackway delivering said articles selectively to said chutes in accordance with the position of each article as it enters the trackway.

9. In a device for sorting substantially cylindrical articles having one face of smaller diameter than the other which will stand on edge, such as stopper tops or the like, and which are fed to the device on edge with some of the articles facing in one direction and some in the opposite direction to position the articles all in one direction with a selected flat face disposed upwardly, the combination of an inclined trackway having a relatively narrow delivery end and a gradually widening discharge end, means for delivering said articles to said trackway on edge at the delivery end thereof, a wide, flat, unobstructed orienting surface on said trackway between the ends which is more than twice as wide as the width of said articles in an axial direction and down which said articles freely and unobstructedly roll on edge in an arcuate path from said delivery end toward said discharge end, guide members against which the articles are directed in their arcuate

movement along said trackway with the small diameter face of each article lying in engagement with one of said guide members, a central projection in said trackway spaced from the entrance end thereof for guiding articles moving along said trackway selectively toward the right or left thereof, said projection being inclined gradually from the center of the trackway toward the guide members at the outer edges thereof, and a pair of inclined chutes associated with said trackway 10 at the discharge end thereof for changing said articles from a position with their axes parallel to the surface of the trackway to a position with their axes perpendicular thereto, one of said chutes having a right-hand twist and the other a 15 left-hand twist, said trackway delivering said

articles selectively to said chutes in accordance with the position of each article as it enters the trackway.
